UNITED STATES PATENT OFFICE.

SEYMOUR KETCHUM, OF MACON, ILLINOIS.

IMPROVEMENT IN COOKING-STOVES.

Specification forming part of Letters Patent No. 121,053, dated November 21, 1871.

To all whom it may concern:

Be it known that I, SEYMOUR KETCHUM, of Macon, in the county of Macon and State of Illinois, have invented a certain Improvement in Stoves, of which the following is a specification:

My invention relates to an improvement in stoves, so that the long center piece of the top of a stove is prevented from warping.

Figure 1 is a plan of a stove embodying my invention. Fig. 2 is a plan of the standard. Fig. 3 is a sectional view of Fig. 1 taken through the line *x x*.

A is the top plate of a stove. *a a a a* are covers or lids. *B B'* is the long center piece. *C C* are the short center pieces. *D* is the standard, and *E* the top plate of the oven.

The long center piece of the stove is cast in two pieces, *B B'*, being divided in the center, as

shown at *f*. The pieces are rabbeted to prevent smoking. On the under side of the pieces *B B'* are flanges *b b'*, which fit in mortises or gains *d d'* in the standard *D*. These mortises are cast at right angles, so that when desired the long center piece can be turned across the front or back of the stove. The standard *D* is cast on the top plate *E* of the oven.

I do not broadly claim the standard.

I claim as my invention—

The division of the long center piece of a stove in two pieces, *B B'*, flanges *b b'*, in combination with the mortises *d d'*, standard *D*, and plate *E*, substantially as described.

SEYMOUR KETCHUM.
